US0D1058955S

(12) **United States Design Patent** (10) **Patent No.:** **US D1,058,955 S**
(45) **Date of Patent:** **** Jan. 21, 2025**

(54) **COMPONENT OF ANIMAL WATERING APPARATUS**

(71) Applicant: **Erik Joseph Diedrichsen**, West Bridgewater, MA (US)

(72) Inventor: **Erik Joseph Diedrichsen**, West Bridgewater, MA (US)

(**) Term: **15 Years**

(21) Appl. No.: **29/932,694**

(22) Filed: **Mar. 14, 2024**

Related U.S. Application Data

(62) Division of application No. 29/870,717, filed on Feb. 2, 2023, now Pat. No. Des. 1,030,154.

Primary Examiner — Susan Moon Lee

CLAIM

The ornamental design for a component of animal watering apparatus as shown and described.

DESCRIPTION

FIG. 1 is a left front top perspective view of a component of animal watering device.

FIG. 2 is a right bottom rear perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken lines depict unclaimed features of the component of animal watering apparatus and form not part of the design claim.
